UNITED STATES PATENT OFFICE.

WILLIS E. NEWTON, OF NEWBURG, IOWA.

FARM-GATE.

SPECIFICATION forming part of Letters Patent No. 585,224, dated June 29, 1897.

Application filed February 15, 1896. Serial No. 579,372. (No model.)

To all whom it may concern:

Be it known that I, WILLIS E. NEWTON, a citizen of the United States, and a resident of Newburg, in the county of Jasper and State 5 of Iowa, have invented a new and useful Farm-Gate, of which the following is a specification.

The object of this invention is to provide an improved gate and improved means for sliding said gate longitudinally and guiding 10 and supporting said gate during its movements.

My invention consists in the construction, arrangement, and combination of elements hereinafter set forth, pointed out in my claim, 15 and illustrated by the accompanying drawings, in which—

Figure 1 is a perspective showing my gate in an open position and means whereby the same may be operated. Fig. 2 is a plan of the 20 mechanism whereby the gate is operated by engagement of a vehicle. Fig. 3 is a detail elevation of the spring mechanism for relieving the shock occasioned by the sudden operation of the gate. Fig. 4 is a view illustrating 25 a clutch mechanism employed in the operating mechanism.

In the construction of the device, as shown, the numerals 10 11 designate supporting-posts and limit and determine the degree of travel 30 of the gate. The posts 10 11 are connected at their upper ends by a rider 12, and on one side of said rider is mounted a track 13, preferably made of metal and laterally removed a short distance from the face of said rider. 35 Hangers 14 15 are provided and carry on their upper ends grooved rollers 16 17, which rollers rest and travel upon the upper edge of the track 13. The lower end portions of the hangers 14 15 are connected to the upper ends 40 of stiles 17 18, forming the ends of the gate. The lower ends of the stiles 17 18 are connected by parallel bars 19, separated a slight distance and forming the lower edge of the gate. A center post or stile 20 is situated midway between the stiles 17 18 and is connected at its lower end to the central portion of the bars 45 19 and secured to the end portions of said bars by braces 21 22, extending from said end portions to points of attachment to the stile 20 near its upper end, thus forming a truss to support the central portion of the gate. Bars 23 are horizontally placed in parallel

planes and are connected to the stiles and braces to form the middle and upper portion of the gate.

55

Posts 24 25 are provided and located at the opposite side of the roadway or passage from the post 10 and on opposite sides of the gate. The post 25 is employed to receive and support the ends of the wires or boards forming 60 the fence at that side of the roadway. The upper end portions of the posts 24 25 are bifurcated, and levers 30 31 are mounted for oscillation therein. The end portions of the levers 30 31 adjacent to the gate are confined 65 within the bifurcations of the posts 24 25 and move vertically therein when the levers 30 31 are oscillated. The extreme inner end portions of the levers 30 31 extend almost to the space through which the posts 17 18 of the 70 gate travel, and connecting-rods 32 33 are hinged thereto and depend therefrom. A slot 34 is formed in the upper portion of the stile 20, and an operating-lever 35 of U shape traverses said slot and is pivoted at its ends 75 to the lower portions of the posts 24 25.

The end of the U-shaped frame formed by the operating-lever 35 is movable vertically in the slot 34, and said slot is enlarged laterally at its lower end to form seats for the end 80 of the frame when the gate is closed or entirely open. By means of the seats in the lower end of the slot 34 the lever is retained against elevation by any movement or oscillation of the gate, thereby locking the gate 85 against longitudinal movement until such time as the lever is elevated in the desired manner. The lower ends of the connecting-rods 32 33 are pivotally connected to the central portions of the opposite bars or arms of 90 the lever 35.

Guide-posts 36 are set midway between the posts 24, 25, and 10, and guide-posts 37 37 are set midway between the posts 24, 25, and 11, all of which guide-posts are short and have 95 journaled on their upper ends antifriction-rollers 38, designed to engage the extreme outer faces of the bars 19 and guide and strengthen the gate in its longitudinal movement.

100

In order to open the gate, it is necessary, if on foot, to elevate the lever 35 manually and then move the gate longitudinally. When it is desired to open the gate while mounted,

the operator depresses one or the other of the outer ends of the levers 30 31, thus oscillating the levers on their fulcrums, elevating the connecting-rods 32 33, and elevating and carrying the lever 35 through an arc, during which operation the cross-head or closed end of the lever 35, engaged in the slot 34, moves vertically in said slot and impels the gate in the desired direction until the said lever passes 5 a vertical plane, after which the momentum attained in the initial operation carries the gate into the position shown. During the longitudinal movement of the gate the rollers 16 17 travel on the track 13, which, being formed 10 of metal and of slight transverse dimension, offers but slight support for snow, sleet, or other obstruction to the travel of the wheel. There are provided, in addition to the construction heretofore set up, arms 50 51, fixed 15 to and extended in opposite directions from those portions of the lever 35 pivoted in the posts 24 25. The arms 50 51 extend at right angles to the path of travel of the gate to such distances as will exceed the length of an ordinary vehicle and the team attached thereto. The outer end portions of the arms 50 51 are provided with miter-gears 52 53, which mesh with miter-gears 54 55, respectively pivoted on vertical axes in boxes 56 57. Arms 58 59 20 are pivoted to the axles of the gears 54 55, and extend therefrom transversely of the roadway and across the line of travel of at least one wheel of an ordinary vehicle. The arms 58 59 are provided with sleeves 60, loosely mounted 25 thereon and revolute relative thereto. The sleeves 60 are about four inches in diameter and are placed from three to six inches above the surface of the ground. Owing to the location and size of the sleeves the wheels 30 will not ride thereon but will push the same downwardly and forwardly until the arms 58 59 are at such oblique angles to the roadway as that the wheels will pass the same. In the forward movement of the arms the sleeves 35 are depressed into contact with the ground and roll thereon, thus flexing the spring 61 to such an extent as that said spring will throw the arms back when the wagon-wheel has passed. Springs 61 are mounted in the 40 boxes 56 57 and impinge against the under side of the arms 58 59 and tend to maintain said arms in normal positions transversely of the roadway and in planes somewhat elevated from the surface of the ground. A ratchet-55 tooth 62 is formed on each of the arms 58 59 and is designed for engagement at times with

ratchet-teeth on the gear-wheels 54 55, but said teeth normally are elevated above the wheels and are maintained at such elevation by the springs 61. An eye 63 is formed in 60 the operating-lever 35, and a curved bar 64 is loosely mounted therein and connected at its ends to a right-angled frame 65, loosely mounted on those portions of the operating-lever connected to the arm 51. Expansive 65 coil-springs 66 67 are mounted on the curved bar 64 and confined between the ends of said bar and the lever 35.

In the practical operation of the gate the triangular frame strikes the ground or a block 70 provided therefor, which results in a compression of one or the other of the springs 66 67 and a consequent cushioning of the cessation of movement of the gate. The gate being closed, as a vehicle approaches one of the 75 wheels of the vehicle engages the sleeves 60 on the adjacent bar 58 or 59 and moves said bar laterally into the position shown by dotted lines. In the movement of the bar laterally it is also moved downwardly, the tooth thereon 80 engages with the ratchet of the gear and rotates said gear, which in turn rotates the gear meshing therewith and the arm connected thereto and throws the operating-lever and the gate thereon into an open position. 85 When the arm has been moved laterally a sufficient degree, the wheel passes and the spring connected to said arm throws the same back into the transverse position and out of engagement with the ratchet on the gear-wheel. The further travel of the vehicle actuates the lever by engagement with the bar on the other side of the gate to restore said gate to a closed condition. 90

I claim as my invention— 95

A sliding farm-gate, comprising a traveling gate having a vertical slot in its central portion, an operating-lever fulcrumed adjacent to said gate and traversing said slot, arms formed on said operating-lever, intermeshing 100 miter-gears connected with said arms, laterally-extending arms clutched to said gears and extending over the roadway, springs for normally retaining said arms in and returning said arms to desired positions and sleeves 105 on said arms for engagement by vehicle-wheels, as set forth.

WILLIS E. NEWTON.
